UNITED STATES PATENT OFFICE

JONATHAN O. CHANEY, OF NORTH HOLLYWOOD, CALIFORNIA

TOP RACK FOR AUTOMOBILES

Application filed September 8, 1930. Serial No. 480,458.

This invention pertains to automobile racks or parcel carriers and especially to a rack adapted to be set up section by section by an individual person and arranged over and above the top of an automobile.

As is well known, automobile tops vary greatly in width and length and also in the degree of curvature, and it is a particular object of the present invention to provide a top rack which may, by a single individual, be readily adjusted in position on an automobile regardless of the difference in the crown of the top and of its length and width and, in this connection, it is an object to provide means for rigidly adjusting the top rack in any of its several vertically adjustable positions with respect to the solid eaves along the sides of the crowned top. A further object is to provide for the adjustment of supporting means laterally to accommodate the rack to different widths of tops and to effect the rigid setting of the rack on the adjusted supporting means and, in this connection, it is a further object to provide positive means for drawing the supporting means inwardly with respect to the rack to accomplish its firm support against solid side eaves along the base of the top crown.

It is especially desirable to provide a mounting means capable of gripping the eaves of the crown and being of such character as not in any manner to interfere with the opening and closing of the side doors of the vehicle.

This invention consists in certain advancements in this art as set forth in the ensuing disclosure and having, with the above, additional objects and advantages, and whose construction, combination and details of means, and the manner of operation will be made manifest in the description of the herewith illustrative embodiment; it being understood that modifications, variations and adaptations may be resorted to within the scope, principle and spirit of the invention as it is more directly claimed hereinafter.

Figure 1 is a perspective of a portion of an automobile showing the improved rack mounted on its top eaves and in a position over and above the car top.

Figure 2 is a perspective of one unit of the rack bottom.

Figure 3 is a perspective of coordinate ends of a cross or end section and a bottom supporting side section.

Figure 4 is a perspective of a part of one of the frame end sections and its supporting bracket device.

A great preponderance of automobiles, at this time, are of the so called closed type and have side doors which close, at the top, close to the eaves E which form securing means for the top cover C. The eaves extend along the sides of the car frame top members F and are, therefore, very rigid and provide a non-yielding base or foundation against which may be contracted vise-like acting side gripping members 2, whose lower ends may have inner frictional facing 3 to protect and to non-slidably engage the top holding or binding eaves E.

From this it will be seen that means are provided which are capable of being drawn vise-like against the solid, frame-supported top eaves.

These gripping members extend vertically and are slidably mounted in downturned bracket limbs 4, which are slotted at 5 to receive bolts 6 whereby the grippers 2 can be set at a desired adjusted position determined according to the height of the crown of the top C above its fastening eaves E.

The bracket members include inwardly and horizontally directed limbs 7, slotted at 8 to receive fastening screws or bolts 9 passing through laterally extending plates 10, adjustable on the bracket 7 to a position determined by the width of the top C; the plate 10 and the bracket 7 being rigidly clamped together in safe, non-shifting position by the fastening bolts 9.

The plates 10 extend from end members 11, of which a pair is provided and which are adapted to be thrown transversely across the top of the vehicle by an individual setting up the rack; the end members being rigid with the plate 10 and being provided with downturned lugs 12, receiving hooks 13 of a draw-bolt device by which the brackets 7, of which there is one at each corner of the frame, may

be positively drawn inward so as to contract the grip members 2 against the horizontal top eaves 3.

This draw-bolt device includes a threaded tube 14, fixed to the hook 13 and receiving a bolt shank 15, whose head 16 can set in against a shoulder 17 of the bracket 7.

It will be seen from the above that the end frame members 11 can be set up easily by a single person in temporary arrangement for the application of longitudinal side frame members 20, which are adapted to be secured detachably, at will, to the coordinate and adjacent ends of the frame members 11.

15 A means is shown for readily interlocking the frame sections 11 and 20 and the said means may consist of top corner hooks 11^a on the members 11 and reverse corner hooks 20^a on the members 20 and mutual reverse hooks 20^b and 20^b at the lower corner of the frame members. When the members have been interhooked, they are securely fastened by means of a dog or latch 21, pivoted at 22 against the face of the member 11 so as to be pressed down across the top of the opposed hook 20^b after which they may be fastened in dogging position as by a cotter pin 23, insertable through the register holes 24 and 25 in the dog and frame member.

30 The side frame members 20 are provided with inwardly directed shelf flanges 26 and on these are supported a rack bottom which preferably consists of a plurality of units 27, which are shown as of lattice construction or form, thus achieving strength and lightness.

After the side members 20 have been properly adjusted and locked then the cross or bow members 11 can be securely fastened by their bolts 9 to the bracket 7 after these have been very securely drawn in by the vise bolts 15, which draw the gripping members 2 in against solidly backed up top eaves E.

From the above it will be seen that the tire rack is of collapsible form and can be easily and quickly set up, member by member, over and above the car top C through a simple, practical and thoroughly reliable fastening means, having its foundational support against the rigid body frame supported top eaves all without in any manner obstructing the opening and closing of the doors D.

In cases where heavy luggage is to be carried, or where the roadways may be extremely rough and for the purpose of preventing longitudinal shifting of the carrier due to inertia, incident to the sudden application of the brakes, there may be used, if so desired, a set of end guys, having hooks 28 adapted to be caught over the visor hood V and over the terminal bottom of gutters G; these guys including turnbuckle sleeves 29 on screw shanks 30, which are hooked to bracket limbs 7. Therefore, when the guys are tensioned up, they firmly hold the rack against longi-

tudinal shifting movement with respect to the top C.

What is claimed is:

1. A top rack for automobiles including a frame structure having individually applicable bow sections, vertical gripping members slidable laterally on said sections for adjustment according to width of the top, and means attached to the frame for positively drawing said members inward against the side eaves of the top.

70 2. A top rack for automobiles including vertically extensible gripping members and a section on which they are slidable laterally for adjustment according to width of the top, and means attached to the section for positively drawing said members inward against the side eaves of the top, said means including draw bolts connecting the said section and the said gripping members.

80 3. A top rack for automobiles including independent, individually applicable end members each of which has an end plate, a sliding corner bracket, and means for rigidly securing said bracket to said plate in various adjusted positions and said means including clamp bolts passing therethrough through the plate and the bracket.

85 4. A top rack for automobiles including a frame structure comprising a pair of separate end members each of which has an end plate, a sliding corner bracket, means for rigidly securing said bracket to said plate in various adjusted positions, and means connecting said plate and its bracket for positively drawing the said bracket inwardly to desired position, and side frame members attachable to the set up end frame members.

90 5. A top rack for automobiles including a frame structure comprising independent transverse end members each of which has an end plate, a sliding corner bracket, means for rigidly securing said bracket to said plate in various adjusted positions, means connecting said plate and its bracket for positively drawing the said bracket inwardly to desired position; said bracket including a vertically

100 adjustable gripping member for adjusting the height of the rack according to the height of the top, means to set the member securely in adjusted position and side frame members applicable to the set in members; all forming an elevated support over the top for a separable tray.
